UNITED STATES PATENT OFFICE.

CALVIN R. DAVIS, OF ROCKFORD, ILLINOIS, ASSIGNOR TO EMERSON-BRANTINGHAM COMPANY, OF ROCKFORD, ILLINOIS, A CORPORATION OF ILLINOIS.

HAY LOADER.

Application filed March 12, 1925. Serial No. 14,874.

This invention relates to hay loaders and has for its primary object the provision of improved means for raising and lowering the delivery end of the elevator frame for the purpose of obtaining a low delivery of the hay onto the rack when starting to load and subsequently obtaining a higher point of delivery as the loading progresses. The principal advantage is that the hay delivery is closer to the rack than with those constructions having a fixed or rigid elevator frame which delivers at all times from the highest point with the result that the hay is frequently blown away after delivery and before it reaches the rack, especially during the early stages of the loading.

My invention contemplates, more particularly, the provision of a simple and practical device for raising and lowering the delivery end of an elevator frame upon and with respect to the frame proper and for locking said delivery end either in the elevated position or in one or more intermediate positions.

Another purpose is to provide an improved elevator frame structure in which the side boards at the upper end move with the movable section or delivery end of the elevator frame.

Other objects and attendant advantages will be appreciated by those skilled in this art as the invention becomes better understood by reference to the following description when considered in connection with the accompanying drawings, in which—

Figure 1 is a side elevation of the delivery end of a hay loader elevator frame embodying my invention;

Fig. 2 is a fragmentary top view of the parts shown in Fig. 1 taken perpendicular to the plane of said frame;

Figs. 3 and 4 are fragmentary side views looking at the opposite ends of the crank device for raising and lowering the delivery end of the elevator frame; and

Fig. 5 is a detail section taken on the line 5—5 of Fig. 2.

Inasmuch as my invention relates only to the construction of the delivery end of a hay loader elevator and to the means for raising and lowering this end, I have deemed it advisable to show in the drawings only these parts. It will be understood that my invention is not confined to any particular frame construction nor to the construction

herein disclosed of the elevator frame and the movable delivery end section thereof, except as especially pointed out in the claims.

The only parts of the main frame shown in the drawings are uprights in the form of angle iron bars 7 and 8 and upwardly inclined angle iron side bars 9 and 11 secured at their upper ends by bolts 12 to the upright bars 7 and 8 respectively. These bars, located at the sides of the elevator frame, constitute the uppermost part of the main frame and provide the immediate support for the upper portion of the elevator frame and the movable delivery end section of said elevator frame. Said upright frame bars 7 and 8 are joined and held in rigid relative relation by a frame cross-bar 13 the ends of which are secured to the upright bars by bolts 14.

The elevator frame comprises main carrier tracks or rails 15 and 16 preferably in the form of angle iron bars arranged with one of the flat angles uppermost to provide tracks for the endless elevating carrier designated generally by 17. Said main track bars terminate at their upper ends just above the main frame cross-bar 13 and are suitably secured thereto as by bolts 18. Suitable bracing and tie connections (not shown) are provided for properly supporting the main track bars on the main frame.

The delivery end of the elevator frame comprises a movable end section or continuation of the main track bars pivotally mounted at the juncture therewith and adapted to be swung upon such mounting to raise and lower the delivery end. In this instance, the movable end section comprises delivery end track bars 19 and 21 held in rigid spaced relation by intermediate cross-bars and braces 22. These tracks 19 and 21 are similar in shape to the main tracks 15 and 16 and are in longitudinal alignment therewith so as to form a continuation of the main elevator frame. To each track 19 and 21 is secured by bolts 23 a plate 24 pivotally connected at 25 to an angle bracket 26 secured to the frame cross-bar 13, thus establishing the pivotal mounting of the delivery end section upon the main part of the elevator frame. In order to provide continuous track surface for the carrier past the break between the track sections each plate 24 is extended downwardly as at 27 to overlap the break and is confined at its lower end by a

guard plate 28 secured to the adjacent main track bars.

The endless carrier 17, of any suitable or preferred construction, is trained at its upper end over pulleys 29 mounted on a shaft 31 which is suitably supported by adjustable brackets 32 on the uppermost end of the track bars 19 and 21. It will be manifest that the upper reach of the carrier rides 10 on the track bars of the main and delivery end sections of the elevator frame at all times, and that said delivery end section is adapted to be swung downwardly from the full line position shown in Fig. 1 to the 15 dotted line position without disturbing or interfering with the function of the carrier, the lower reach of which is guided over idler pulleys 33.

In order to retain the hay on the delivery end section from sidewise displacement in 20 all positions of said section, I have provided movable side boards 34 which are pivoted at 35 on the upper ends of the main side boards 36 in turn secured to the upright frame bars 7 and 8. Tie links 37 pivotally connect the movable side boards 34 to the movable track bars 19 and 21 and hold said side boards in proper relation to the movable end section in all positions of the latter.

25 The means for raising and lowering the delivery end of the elevator frame will now be described. This means comprises, generally stated, an operating member preferably, but not necessarily, in the form of a hand crank connected with the delivery end section and adapted to lock beyond a dead center position for holding it in the elevated position, and a counter-balancing means such as a coiled spiral spring for aiding in raising 40 said delivery end section. Said means also includes, but not essentially, provision such as a ratchet device for holding the delivery end section in one or more intermediate positions. In the preferred embodiment the hand crank 38 is integral with a supporting rock-shaft 39 mounted in brackets 41 and 42 fixed to the inclined side bars 9 and 11, respectively, of the main frame at an elevation within convenient reach of an operator 45 standing on the ground. On the end of the rock-shaft opposite from the crank 38 is fixed a crank arm 43 in the same angular plane as the hand crank. The hand crank 38 and crank arm 43 are respectively attached to the upper or outer end of the delivery end section by means of a flexible connection comprising a link 44 connected to the crank element, a chain section 45 trained over a guide pulley 46 mounted on 50 the upper end of the adjacent upright frame bar 7 or 8, as the case may be, and a link 47 connected to the adjacent end of the upper carrier shaft 31. Manifestly, the delivery end section may be raised and lowered 55 by manipulation of the hand crank 38. As

shown in Fig. 4 the hand crank 38 has been swung in a counter-clockwise direction to elevate the delivery end section to the highest position and has moved slightly beyond a dead center position limited by fixed stops 48 thereby locking the delivery end of the conveyer in the highest position. In other words, the pivoted points 49 of the connecting links have been carried beyond the center of the rock-shaft 39 and the weight of 60 the delivery end section translated into upward pull on the links 44 holds the latter against the stops 48.

In order to counter-balance to a substantial degree the weight of the delivery end section and to aid in raising it I employ a coiled spiral spring 51 on the rock-shaft 39 connected at one end 52 to a fixed part and at its opposite end 53 to a part 54 fixed but rotatably adjustable upon and with respect to the rock-shaft 39. In this instance, the part 54 has a clutch connection with a complementary clutch part 55 secured to the rock-shaft 39. By reason of the clutch connection thus provided the spring 51 may be put under 65 the desired tension and will function to counter-balance the weight of the delivery end sections, as will be obvious. This pressure likewise tends to hold the crank members in the locked position.

In the use of my invention, when starting to load, the delivery end of the elevator frame will be dropped to the lowest position shown in dotted lines in Fig. 1, simply by swinging the hand crank 38 forwardly 10 beyond the dead center position, that is, in a clockwise direction viewing Fig. 4. A low hay delivery will thus be obtained; and when the load is high enough the attendant on the load will take hold of the delivery end of the movable section and swing it upwardly to the highest position at which it will be automatically locked by reason of the construction above described for this purpose.

105 In the event that it is desired to hold the delivery end section at one or more intermediate positions I have provided a pawl 56 mounted on a fixed center with respect to the frame and adapted to engage in one or more notches 57 in a ratchet part fixed to the rock-shaft, as shown in Fig. 4. The pawl is so arranged that when in the position shown it will drop into the first notch and any succeeding notch for holding the delivery end section in successive intermediate positions. If these positions are not desired the pawl may be swung in a clockwise direction where it hangs in an inoperative position so as not to function.

110 It will be manifest to those familiar with this art that the improvement disclosed herein provides a simple and practical means for accomplishing the purpose intended; that the raising of the delivery end section 115

- may be accomplished without the necessity of the attendant on the load getting down to operate devices positioned at a low point on the loader as is necessary in certain prior constructions; that the several operations may be performed quickly and easily and with comparatively little effort on the part of the attendant; and that the structure comprises such few parts so constructed that they may be produced at a comparatively low cost, consequently not materially affecting the manufacturing cost of a hay loader.
- It is believed that the foregoing conveys a clear understanding of the objects presented above and while I have illustrated but a single working embodiment it should be understood that changes might be made in details of construction without departing from the spirit and scope of the invention as expressed in the appended claims, in which—
- I claim:
1. In a hay loader, in combination, an elevator frame having a delivery end adapted to be raised and lowered, and means for so moving said delivery end including an operating device movable past a dead-center position for holding said delivery end in the raised position, and spring means normally tending to operate said device toward its dead center position whereby when said frame is raised at the delivery end said device is automatically operated toward dead center position to hold the same raised.
  2. In a hay loader as set forth in claim 1, the provision of means in connection with said operating device for holding said frame raised in intermediate positions less than the elevation corresponding to the dead center position of said device.
  3. In a hay loader as set forth in claim 1, the provision in connection with said operating device, of a ratchet and detent for holding said frame raised in intermediate positions below the elevation corresponding to the dead center position of said device.
  4. In a hay loader, in combination, a main frame, an elevator frame thereon including a pivoted delivery end section adapted to be swung to raise and lower its delivery end, a rock-shaft mounted on the main frame, extending crosswise thereof, and having a crank-arm at each end, a connection between each crank-arm and the delivery end of said pivoted elevator section, means operable to turn said rock-shaft to raise said elevator section, said crank-arms and connections serving when in dead center relation to hold said delivery end section raised, and spring means normally under a tension to aid in raising the elevator section and serving when said section is raised by its delivery end to operate said crank arms automatically toward their dead center holding positions.
  5. In a hay loader as set forth in claim 4, the provision in connection with said crank arms and their connections, of a ratchet on said rock-shaft and a pawl on a relatively stationary part of the hay loader arranged to engage the ratchet to hold said elevator section raised to intermediate positions below the elevation corresponding to the dead center position of said crank arms.
  6. In a hay loader as set forth in claim 4, the provision of a stop on a relatively stationary part of the hay loader for limiting the swinging movement of said crank arms to determine thereby the proper dead center holding position thereof.
  7. In a hay loader, in combination, an elevator frame having a pivoted delivery end section adapted to be raised and lowered, a shaft extending transversely beneath the elevator frame and having a crank-arm at each end, a connection between each crank-arm and the adjacent side of the pivoted elevator section at its delivery end whereby to raise the latter by turning the shaft, and means for limiting movement of the crank connections beyond a dead-center position to hold the pivoted elevator section in the raised position.
  8. In a hay loader, in combination, a main frame including forwardly and upwardly inclined side bars and upright side bars fixed to the upper ends of said inclined side bars and extending above the latter, a pulley mounted on the upper end of each upright side bar, a cross-bar connecting said upright side bars, an inclined elevator frame attached to said cross-bar and having a pivoted delivery end section adapted to be swung vertically to raise and lower its delivery end, a shaft interposed between and mounted on said inclined side bars, a crank-arm on each end of said shaft, a connection between each crank-arm and the pivoted elevator section, each connection being trained over the pulley at the adjacent side of the frame, and means whereby said shaft may be turned to raise the pivoted elevator section through operation of said connections.
  9. In a hay loader, in combination with an elevator frame having a pivoted delivery end section adapted to be raised and lowered, of a crank-shaft the crank-arm of which is connected to said pivoted section to raise the latter, means whereby movement of the crank-arm is limited beyond a dead-center position to hold the pivoted section in the raised position, and a coiled spiral spring on the crank-shaft counteracting the weight of the pivoted elevator section.
  10. In a hay loader, in combination with an elevator frame having a pivoted delivery end section adapted to be raised and lowered, of a crank-shaft the crank-arm of which is connected to said pivoted section to raise the latter, means whereby movement of the crank-arm is limited beyond a dead-center

- position to hold the pivoted section in the raised position, and a coiled spiral spring on the crank-shaft counteracting the weight of the pivoted elevator section and adapted to automatically move said crank-arm beyond said dead-center position when said pivoted elevator section has been raised. 5
11. In a hay loader, an elevator frame having a pivoted delivery end section arranged to be raised and lowered for cooperation with a hay receiver, such as a rack, and means for automatically holding said elevator delivery end section in raised position when it has been moved to such position from the delivery end thereof as, for example, from the rack. 10
12. In a hay loader, the combination with an elevator frame having a pivoted delivery end section adapted to be raised and lowered, of a crank-shaft the crank arm of which is connected to the pivoted section to raise the latter, means whereby movement of the crank arm is limited so as not to go beyond a dead center position wherein the pivoted section is held in raised position, and means counteracting the weight of the pivoted elevator section and serving automatically to move said crank-arm toward said dead center position when the pivoted elevator section is raised. 15
13. In a hay loader, in combination, a main frame, an elevator frame thereon having a pivoted delivery end section adapted to be raised and lowered, a transverse shaft on the main frame having a crank-arm at each end, a connection between each crank-arm and the adjacent side of the pivoted section at the delivery end thereof adapted by turning movement of said shaft to raise said section, a coiled spiral spring on said shaft connected at one end to a part fixed with respect to the main frame and at its opposite end to said shaft, one of said spring connections being adjustable to increase the spring tension, said spring serving to 20 counteract the weight of the pivoted end section. 30
14. A hay loader as set forth in claim 13, in which said crank connections are movable past a dead-center for locking the pivoted elevator section in the raised position and in which said spring serves to hold said connections in the locked position. 35

CALVIN R. DAVIS.
